DRIVER'S GLOVE

Louise V. Starek, Parma, Ohio

Application December 17, 1952, Serial No. 22,738

Term of patent 7 years

(Cl. D3—11)

To all whom it may concern:

Be it known that I, Louise V. Starek, a citizen of the United States, residing at Parma, county of Cuyahoga, and State of Ohio, have invented a new, original, and ornamental Design for a Driver's Glove, of which the following is a specification, reference being had to the accompanying drawing, forming part hereof.

Fig. 1 is a rear elevational view of a driver's glove showing my new design;

Fig. 2 is a sectional view taken on the line 2—2 of Fig. 1, and

Fig. 3 is a front elevational view, on reduced scale, of the driver's glove shown in Fig. 1.

The essential features of the design are shown in full lines.

I claim:

The ornamental design for a driver's glove, as shown and described.

LOUISE V. STAREK.
